U. W. WALTON.
AUTOMATIC TRIP.
APPLICATION FILED FEB. 26, 1914.

1,115,353.

Patented Oct. 27, 1914.

UNITED STATES PATENT OFFICE.

ULRICH W. WALTON, OF PATON, IOWA.

AUTOMATIC TRIP.

1,115,353.

Specification of Letters Patent. Patented Oct. 27, 1914.

Application filed February 26, 1914. Serial No. 821,250.

To all whom it may concern:

Be it known that I, ULRICH W. WALTON, a citizen of the United States of America, residing at Paton, in the county of Greene and State of Iowa, have invented certain new and useful Improvements in Automatic Trips, of which the following is a specification, reference being had therein to the accompanying drawing.

10 This invention relates to automatic trips for throwing the brakes of a train in case the same should run by a danger signal which has been set by means of the semaphore arm or other indicating device.

15 Another object of this invention is the production of a simple and efficient means for setting the trip simultaneously with the setting of a danger signal so as to be in proper position to engage the desired cut-off adapted to be carried by a locomotive in order that the brakes may be automatically operated in case a train or locomotive should pass a danger point.

20 With these and other objects in view this invention consists of certain novel combinations, constructions, and arrangements of parts as will be hereinafter fully described and claimed.

25 In the accompanying drawings:—Figure 1 is a transverse sectional view through a track and the casing which supports the automatic trip. Fig. 2 is a detail perspective of the casing showing the trip applied thereto. Fig. 3 is a section taken on line 3—3, of Fig. 1. Fig. 4 is a section taken on line 4—4, of Fig. 1 looking in the direction of the arrow. Fig. 5 is an enlarged vertical section showing the manner of attaching the stop arm to the main trip supporting shaft. Fig. 6 is a detail perspective of the stop arm used in connection with the present device. Fig. 7 is a transverse sectional view through the sprocket wheel over which the operating sprocket chain is 30 adapted to pass. Fig. 8 is an embodiment of the valve engaging blade showing the same provided with a means for permitting a light to constitute a signal therefor.

35 By referring to the drawings it will be seen that 1 designates the usual track upon which the locomotive or other vehicle 2 is adapted to pass. The locomotive is adapted to carry a valve 3 which carries a projecting finger or lever 4 adapted to project beyond the side of the train. The valve 3 is carried preferably in the rear of the pilot

although the same may be carried in any desired or convenient position upon the locomotive or engine. The present invention, however, deals more especially with the construction of the automatic trip *per se* and not with the construction of the valve or train pipe construction which may be made in any desired or convenient manner.

40 A casing or receptacle 5 is preferably placed to one side of the track and beneath the road bed thereof as is illustrated clearly in Fig. 1. This casing or receptacle 5 is preferably made water tight so as to prevent the entrance of moisture which would 45 be likely to corrode or interfere with the working portions of the automatic trip. A bearing block 6 is carried in the bottom of the receptacle or box 5 and within this bearing block 6 is journaled the reduced portion 50 of the operating shaft 8.

45 The operating shaft 8 is preferably square throughout the major portion of its length and upon this square portion of the operating shaft 8 is placed a sprocket wheel 9. This sprocket wheel 9 is provided with a plurality of sprocket teeth 10 over which the sprocket chain 11 passes for the purpose of rotating the operating shaft 8 when it is so desired. This sprocket wheel 9 is provided with a circumferential flange 12 around the lower edge thereof, which flange extends beyond the sprocket teeth 10 of the sprocket wheel 9 and constitutes a supporting ledge for the sprocket chain as is clearly 55 illustrated in Figs. 1, 3 and 7. By means of the flange 12 it will be seen that the chain 11 will be held in its correct position and will not be likely to become detached from the sprocket wheel by slipping from the 60 sprocket teeth 10. The sprocket chain 11 is secured to a plurality of operating cables 13, which cables may pass to the usual signal device for coöperating with the semaphore arm or other signal for operating the 65 chain 11 simultaneously with the operation or setting of the signal so as to cause the trip hereinafter described to be correctly set at the same time the signal is set in a danger position. It, of course, should be understood that the cables 13 may be passed through any desired form of conduit or means for conveying the cables to the desired point.

70 A removable cap or plate 14 is secured to the top of the receptacle or box 5, and this cap supports a plurality of depending stop

lugs 15, which stop lugs are provided with enlarged heads and are also provided with clamping nuts 16 threaded thereon for firmly securing the stop lugs 16 in engagement with the cover plate 14. The stop lugs 15 are provided with downwardly projecting ends 17, which downwardly projecting ends 17 constitute stops for engaging the stop arm 18, which stop arm is fitted upon 10 the square portion of the operating shaft 8 so as to be swung as the operating shaft 8 is rotated. Two of these stop lugs 15 are employed so as to limit the swing of the arm 18 in each direction. One of the stop lugs 15 will limit the swinging movement of the arm 18 in one direction when the stop has been set to an operative position. The other stop lug 15 will constitute a stop for 15 limiting the swing of the shaft or stop arm 18 in the opposite direction as illustrated in Figs. 1 and 5. The stop arm 18 is provided with an enlarged head 19, which enlarged head is held against sliding movement upon the shaft 8 by means of a thumb nut 20.

20 The operating shaft 8 is provided at its upper end with a rounded portion 21, which rounded portion 21 carries a valve engaging blade 22 extending at right angles to the shaft 8. This valve engaging blade 22 may 25 be colored red upon one face thereof so as to constitute a signal in itself and indicate that the stop is in a danger position. An integral collar 23 is carried by the rounded portion 21 of the operating shaft 8 and fits 30 snugly over the upper end of the supporting sleeve 24 so as to prevent the entrance of moisture or water into the interior of the casing or receptacle 5 by passing downwardly through the operating shaft 8.

35 The sleeve 24 is provided with an enlarged flange portion 25 formed upon its lower end to constitute an efficient bearing for engaging the cover plate 14 of the receptacle or box 5. This sleeve 24 will constitute efficient means for supporting the signal or stop blade 22 in its correct vertical position and prevent the signal or stop blade 22 from sagging.

40 From the foregoing description it will be seen that a very simple and efficient means has been produced for constituting an automatic trip for throwing the brakes of a train in case a train should accidentally pass by a danger signal, and it will be further un-

derstood by carefully considering Figs. 4 55 and 5 that the swing of the stop arm 18 will be limited in both directions so as to prevent the signal from being swung too far after the same has once come into engagement with the trip lever of the automatic 60 brake mechanism. Of course, it should be understood that the device may be modified as to its detail mechanical construction without departing from the spirit of the invention. 65

As is illustrated in Fig. 8 the valve engaging blade 22' may carry an electric or other light, and this valve engaging blade 22' is provided with a red glass plate 23' behind which is placed a light of suitable 70 description in order that the signal may be read in the dark. It of course should be understood that this invention may be applied to the present device without departing from the spirit of the invention. 75

Having thus described the invention what is claimed as new, is:—

1. A device of the class described comprising a casing, a shaft carried within said casing, a stop blade carried by said shaft, said shaft provided with an integral collar, a sleeve carried by said casing, said collar engaging the upper end of said sleeve and limiting the downward movement of said shaft upon said sleeve, stop lugs carried by 80 said casing, a stop arm detachably secured to said shaft and adapted to engage said stop lugs for limiting the swing of said stop arm, and means for rotating said shaft. 85

2. A device of the class described comprising a casing, a shaft carried thereby, a stop blade secured to said shaft, stop lugs carried by said casing, a stop arm carried by said shaft and adapted to engage said stop lugs for limiting the swing of said stop arm, an operating sprocket wheel carried by said shaft and provided with a projecting flange 90 upon the lower face thereof, and a chain passing around said sprocket wheel and resting upon said flange whereby said chain will 95 be held from falling from said sprocket wheel. 100

In testimony whereof I hereunto affix my signature in presence of two witnesses.

ULRICH W. WALTON.
